CENTRALIZED TRAFFIC CONTROL SYSTEM
FOR RAILROADSFrank T. Pascoe, Carnegie, Pa., assignor to The
Union Switch & Signal Company, Swissvale,
Pa., a corporation of Pennsylvania

Application July 17, 1947, Serial No. 761,667

8 Claims.

(Cl. 246—3)

1

My invention relates to centralized traffic control systems for railroads, and more particularly to apparatus for controlling the movement of traffic on stretches of railway track over which traffic may move in either direction and for selecting the direction of traffic movement on either of two parallel tracks such as those comprising the passing tracks which interconnect the successive stretches of single track on single track railroads.

The principal object of my invention is the provision of an improved system for the remote control from a central office of a coded reversible signaling system of the type illustrated in the United States Letters Patent No. 2,390,010, issued November 27, 1945, to Talbert and Staples, but my invention also includes improvements in the wayside circuits of the system of the patent by which the control from the central office is facilitated and improved operation obtained.

The signaling system of this patent is arranged to provide reversible coded track circuit control for those railway signals located at the ends of the passing tracks, which govern the movement of trains into the main track and into the siding, respectively, from the adjoining single track stretches at either end, and is arranged for use in a block signaling system in which the signals which govern traffic movements through the single track blocks are also controlled by coded track circuits, a system for that purpose being shown, for example, in the United States Letters Patent No. 2,344,333, issued March 14, 1944, to J. J. Van Horn, which patent was reissued as No. Re. 22,780 on August 13, 1946. These two systems together provide coded track circuits for all track in the controlled territory except for the short detector sections which include the track switches at the ends of the passing tracks. The coded track circuits not only control the railway signals but in addition provide a system for the control of motor car indicators and for that purpose each coded track circuit is arranged to be normally energized by steady current except when a train movement is authorized. As explained in the Talbert and Staples patent, each motor car or hand car used by maintainers or others in the controlled territory is provided with insulated wheels across which an indicator lamp is connected so as to be normally lighted by current in the track rails. The flashing of this lamp when the track current is coded indicates to the operator of the car that a train may be approaching and that the car should be removed from the track.

2 The remote control system by which the track switches and signals are manually governed from the control office is to be understood to be of the "Time Code" type as described in the United States Letters Patent No. 2,411,375, issued November 19, 1946, to A. P. Jackel.

A feature of my invention is the provision of improved arrangements for governing the transmission of control codes by the remote control system whereby controls are sent to stations at both ends of the passing tracks by the operation of the starting button associated with the signal lever for the entering signal, only when the operation of a traffic relay at the exit end of the block is required in order to effect the clearing of such signal. A further feature of my invention is the provision of means for controlling the order of transmission of the two codes referred to so that the one for operating the traffic relay is not issued until the signal control relay at the opposite end of the block has been reversed. In respect to this feature, my invention is an improvement upon that disclosed in a copending application for United States Letters Patent, Serial No. 708,920, filed November 9, 1946, by F. T. Pascoe and A. L. Jerome.

One form of apparatus embodying my invention will now be described and the novel features thereof will then be pointed out in claims.

30 Referring to the accompanying drawings, Fig. 1 shows the apparatus at the control office, comprising a miniature track diagram of the controlled territory together with the control panels for the two stations of the remote control system at opposite ends of the passing tracks shown in the diagram, while Figs. 2A, 2B, 2C and 2D, when arranged side by side in the order listed, form a view of the corresponding track plan together with the relays and apparatus at each of the two stations.

45 As shown in the drawings, the controlled territory includes the detector sections 1T and 3T for the power operated track switches 1W and 3W together with the intervening double track stretch comprising the track sections AT and BT. The latter are equipped with oppositely directed coded track circuit systems of the type shown in the above-mentioned Talbert and Staples patent, one of which systems controls the opposing main line signals 2RA and 4LA, which govern train movements through section AT, and the other the opposing slow speed signals 2RB and 4LB which govern train movements into the side track section BT.

50 55 The circuits for the control of the leaving

signals 2LA, 2LB, 4RA and 4RB are not shown, but these may be of the type shown in the Van Horn patent above referred to.

The detector sections 1T and 3T are each provided with a conventional track circuit having a track relay 1TR or 3TR normally energized by a track battery TB and controlling a slow acting track repeater relay 1TP or 3TP, while the coded track circuit sections AT and BT are each provided with a set of code transmitting and detecting apparatus at each end. As shown in Fig. 2C, a code transmitter relay LACT is normally energized over a circuit extending from one terminal B of the local source of energy over back contact c of a directional control relay LAPS and the normal contact a of a polar stick traffic relay LAFS through relay LACT to the other terminal C of the local source. Contact a of relay LACT normally connects a track battery TB through relay LATR to the rails of section AT to supply steady current thereto which holds the track relay RATR, Fig. 2B, steadily energized, and relay RATR in turn holds a slow release front contact repeater relay RATF energized. Similarly, in Fig. 2B the code transmitter relay RBCT is normally energized over back contact c of a directional control relay RBPS and contact a of a polar stick traffic relay RBFS, its circuit also including a back contact c of a directional stick relay RBDS, and relay RBCT supplies energy normally from a track battery TB through relay RBTR to the rails of section BT by which the track relay LBTR and its front contact repeater LBTF are normally held energized.

Each of the code following track relays as shown is of the biased polar type as indicated by the arrow on its winding and is so poled that it is nonresponsive to current from the adjacent track battery TB.

Referring to Fig. 1, the relays 1TK, 3TK, ATK and BTK are indication relays governed over code channels identified by the numbers 10 and 12, with suffix a or b, by indication codes transmitted from the field stations by the remote control system of the Jackel patent hereinbefore referred to. Relays 1TK and 3TK are track indication relays which are picked up over channels 10a and 10b upon the release of indication storage relays 1TKS and 3TKS controlled by relays 1TP and 3TP, as shown in Figs. 2A and 2D, respectively, and indicate the occupancy of the detector section 1T or 3T by the lighting of lamp 1TKE or 3TKE in the track diagram, while relays ATK and BTK are block indication relays which are picked up over channels 12a and 12b upon the release of relays RATF and LBTF to indicate the occupancy of the block sections AT and BT by the lighting of lamps AKE and BKE, all of these lamps being normally dark, as shown.

Another function of the code controlled indication relays is to render the control codes ineffective to change the condition of the track circuit system when any of the track sections involved is occupied, back contacts b, c, d and e of these relays being included in the control circuits of Fig. 1 for that purpose.

The control apparatus of Fig. 1 includes two individual panels for the control of the wayside apparatus, that at the left being for the control of the apparatus of Figs. 2A and 2B as indicated, this including a switch lever 1SW, a signal lever 2SG, and a starting button 2STB controlling a starting relay 2ST together with a selector relay 234S which is operated in response

to a control code initiated by relay 2ST to establish a plurality of control channels, and a delivery relay 234D, by which the indication relays are operated in response to an indication code received from the station of Figs. 2A and 2B. The right-hand panel includes a similar set of apparatus for the control of the wayside apparatus of Figs. 2C and 2D. All of this control apparatus is identified by reference characters similar to those of corresponding elements in the Jackel patent and functions as described therein.

In addition, Fig. 1 includes two auxiliary or storing relays 2STS and 4STS, each of which is picked up by the operation of the starting button of the corresponding panel but only if the positions of the switch and signal levers of the panel indicate that the operation of a traffic relay controlled from the other panel is required and that the transmission of two codes is required to set up the desired route. The operation of the storing relay serves to initiate the transmission of the two codes and also insures their transmission in the required order.

The central office control of the track switches is effected by the operation of polar stick control relays 1WS, Fig. 2A, and 3WS, Fig. 2D, over the control channels 1a and 3a, or 1b and 3b, by the switch levers 1SW and 3SW, and the signals associated therewith are governed by the operation of signal control relays 2LHS, 2RHS, 4LHS, and 4RHS controlled over channels 5a and 1a, or 5b and 1b, by the signal levers 2SG and 4SG in the manner described in the Jackel patent. In addition, the remote control system is arranged to operate the traffic relay LAFS, Fig. 2C, and the similar relay RBFS, Fig. 2B, from normal to reverse by the energization of channel 4b or 4a during the transmission of control codes to their respective stations, but these traffic relays are not restorable to normal by code transmission, but only by the energization of the adjacent track relays in response to current received over the track rails from the remote end of the block. Each of these traffic relays controls a slow release repeater relay LAFSP or RBFS by which it is interlocked with the directional control relay LAPS or RBPS which governs the opposite direction of traffic movement.

Each of the track switches 1W and 3W has associated therewith a polarized indication relay such as relay 1WP, Fig. 2A, which is energized in its normal or reverse position only when the switch is locked in a corresponding position, which relay jointly with the associated switch control relay controls normal and reverse switch indication relays such as the relays 1NWP and 1RWP. The switch machines for switches 1W and 3W are of the dual control type provided with a selector lever 1DS or 3DS by which the switch machine may be conditioned for either hand or power operation, each selector relay controlling a repeating relay 1WLS or 3WLS which is energized only when the switch is conditioned for power operation.

The signals as shown are of the searchlight type each having three position mechanisms identified by the letter G prefixed by the signal designation. Each signal mechanism in its de-energized or stop position displays a red light, and, when energized in the direction indicated by the legend Y or G, operates the corresponding circuit controller contacts and displays a yellow or green light to indicate caution or proceed, re-

spectively. Each group of mechanisms in the stop position energizes an indication relay 2RGP, 2LGF, 4RGP or 4LGP and the mechanisms 2LAG and 4RAG for the main line signals 2LA and 4RA control repeating relays 2LAHP and 4RAHP by means of which the caution and proceed aspects of signals 4LA and 2RA located in the rear of signals 3LA and 2RA, respectively, are controlled. Each group of signal mechanisms is controlled by a block repeater or route relay 2RBP, Fig. 2A, or 4LBP, Fig. 2D, governed by the corresponding signal control relay 2RHS or 4LHS, and also by code detector or decoding relays of the coded track circuit system such as relays 2RAH, and 2RBD, or 4LAH and 4LBD, and by a directional stick relay such as relay RBDS or LBDS. Each group of signals has associated therewith a conventional approach locking stick relay such as relay 2RAS or 2LAS, Fig. 2A, or relay 4RAS or 4LAS, Fig. 2D, having back contacts in the circuits for the associated signal mechanisms and front contacts in the circuits for controlling the adjacent track switch and in circuits which control opposing signals. A time element relay such as 1TER or 3TER is provided whereby the energization of each approach locking relay is delayed for an appropriate time interval following the manual return of one of the associated signals to its stop position. The approach locking relays 2RAS and 4LAS also govern section locking relays RAES, Fig. 2B, and LBWS, Fig. 2C, for the detector sections 1T and 3T.

Continuously operating code transmitters 180CT and 75CT are provided at each station which generate coded currents having substantially equal on and off periods by the continuous operation of their contacts at a constant rate of 180 or 75 times per minute, respectively.

In response to the reversal of the traffic relay LAFS, Fig. 2C, by the operator, the circuit for holding relay LACT steadily energized is opened and relay LACT is caused to operate periodically to supply coded current to section AT at its right-hand end by supplying coded current to relay LACT over the circuit extending from terminal B at contact *f* of relay 4LAS, Fig. 2D, over contact *e* of relay 3TP and contact *b* of relay 3WLS to wire 21, or from terminal B over contacts *b* of relays 3RWS and 3WLS to wire 21, and thence over contact *a* of the code transmitter 180CT or 75CT, Fig. 2C, contact *a* of the repeating relay 4RAHP for signal 4RA, the reverse contact *a* of relay LAFS through relay LACT to terminal C. Relay 4RAHP is controlled by the mechanism for signal 4RA so that 75 code is supplied to section AT when signal 4RA is at stop and 180 code when signal 4RA indicates caution or proceed.

The energization of section AT in the opposite direction by coded current is governed by the entering end signal control relay 4LHS of Fig. 2D. The reversal of relay 4LHS when relay LAFS is normal completes a circuit for the directional control relay LAPS from terminal B over contacts *d* of relays 4LHS and 3NWP, wire 22, back contact *a* of relay LAFSP, normal contact *c* of relay LAFS through relay LAPS to terminal C, and relay LAPS becomes energized and its back contact *c* opens to release the normally energized relay LACT and thereby discontinue the supply of steady current to the rails of section AT. The track relay RATR of Fig. 2B therefore releases, deenergizing the slow release repeating relay RATF and energizing a slow release back contact repeating relay RATB, and upon the release of relay RATF, a slow release traffic relay RAES is

picked up over the circuit extending from terminal B over contacts *a* of relays RATR, RATF, and RATEB, contact *c* of relay RAES through relay RAES to terminal C. Relay RAES then completes a stick circuit at its contact *a*, and by closing its front contact *b* completes a circuit for effecting the periodic operation of relay RACT whereby section AT is supplied with 75 code when signal 2LA is at stop and with 180 code when signal 2LA indicates caution or proceed. This circuit extends from terminal B at front contact *b* of relay 1WLS, Fig. 2A, over wire 23, back contact *b* of relay RATR over contact *a* of the code transmitter 15CT to back contact *a* of relay 2LAHP or from wire 23 over contact *a* of the code transmitter 180CT to the front contact *a* of relay 2LAHP and thence over front contact *b* of relay RAES, wire 24 and contact *c* of relay 1RWP to wire 26, or from wire 24 over contact *b* of relay RAES, wire 25, and contact *e* of relay 1TP to wire 26 and thence through relay RACT to terminal C.

The code following track relays LATR and RATR govern decoding apparatus which is generally similar to that of the Talbert and Staples patent referred to. When relay LATR is operated periodically, relay LATF is maintained picked up by periodic energization over contact *a* of relay LATR and completes a circuit from terminal B at its contact *a* over contact *c* of relay LATR to energize the primary winding of the decoding transformer DT3 in such a manner as to cause current of the code frequency to be induced in the lower winding of transformer DT3 and the latter current is rectified by contact *d* of relay LATR to energize the code detector relay 4LAH. When the operation is at the 180 code rate, the decoding relay 4LAD is also energized, through the selective decoding unit 180DU.

When relay RATR is operated periodically, the slow release relays RATF and RATEB are maintained picked up by their alternate energization over contact *a* of relay RATR and if relay RAES is released, the decoding transformer DT1 is energized over back contact *c* of relay RAES and front contact *c* of relay RATEB to render relays 2RAH and 2RAD responsive to the code operation of relay RATR.

Each decoding transformer is provided with a feed back circuit by which impulses of brief duration may be supplied to the track rails during each off period of the received master code. Transformer DT1, for example, supplies impulses through an impulse transformer J1 to briefly energize the associated code transmitter relay RACT during each off period of the master code generated by relay LACT. Feed back impulses are supplied to section AT by the periodic energization of relay RACT over a circuit extending from the upper terminal of transformer J1 over contacts *b* of relays RATEB and RAES and thence over wires 24 and 26 or 26, 25 and 26, as already traced, through relay RACT to terminal C, and thence over the normal contact *b* of the signal control relay 2RHS or front contact *b* of relay 1RWP and wire 27 to the lower terminal of transformer J1. These feed back impulses operate the track relay LATR during the intervals between the impulses of master code supplied by relay LACT, with the result that energy is supplied over contact *b* of relay LATR to the lower winding of relay LAFS, which serves to restore the traffic relay LAFS to normal when section AT is vacated and thereby terminate the code operation of relay LACT, following a left to right train movement over the main track. When section AT is being supplied

with master code in the opposite direction by relay RACT the response of relay LATR to the master code causes transformer DT3 to supply feed back impulses to relay LACT through transformer J3 over front contact *c* of relay LAPS and the normal contact *a* of relay RAFS. Relay LACT therefore supplies feed back impulses to section AT which operate the track relay RATR during the intervals between the impulses of master code supplied by relay RACT. The purpose of the feed back impulses in this case is to maintain relay RATF picked up so as to disconnect terminal B at its contact *b* from the indication channel 12a, the energization of which causes the occupied condition of section AT to be indicated at the office. Contact *a* of the track relay RATR over which relay RATF is energized is closed by the feed back impulses for a small part of each code frequency cycle, and to provide full energization of relay RATF under this condition a snubbing condenser is connected in parallel with its winding over the front contact *d* of relay RAFS, as shown.

It will be seen, therefore, that the block indication is controlled by master code for one direction of traffic movement and by feed back code for the other direction, and that the feed back code for said one direction serves as a means for restoring the traffic relay to normal at the distant end of the block while for the other direction, the traffic relay is restored by the substitution of steady current for the coded current.

Only slow speed train movements are provided for through section BT, and this section is arranged to be supplied with 75 code only, by the transmitter relays RBCT and LBCT, to energize the decoding relays 4LBD and 2RBD, respectively, by the operation of apparatus generally similar to that provided for section AT by which the relays 2RAH and 2LAH are controlled, the energization of relay 4LBD or 2RBD causing the corresponding signal 4LB or 2RB to display a green light below the red light of the main signal to indicate "proceed at slow speed." When a train governed by signal 4LB or 2RB enters the route governed thereby, the directional stick relay LBDS or RBDS becomes energized to maintain the established direction until section BT is vacated, and prepares circuits by which the entering signal for that direction may be caused to display a yellow light below the red light of the main signal to indicate "caution, slow speed" to permit a train to enter the siding occupied by a preceding train moving in the same direction.

The coded track circuit system for section BT in other respects is generally similar to that for section AT, except that it is oppositely directed so as to employ code channels 4a and 12b governed by different coding units of the remote control system for the control of the traffic relay RBFS, Fig. 2B, and for the control of the block indication relay BTK, Fig. 1.

The operation of the system of my invention will now be described under different assumed conditions, starting with the apparatus in its normal inactive condition as shown in each instance.

To clear signal 4LA, the operator moves lever 4SG to its left-hand position with lever 3SW normal, as shown, and presses the starting button 4STB, thereby energizing the starting relay 4ST. Relay 4STS is not operated because its circuit is open at contact *c* of lever 3SW. The closing of contact *b* of relay 4ST supplies energy to a wire 267 which initiates the transmission of a control code as described in the Jackel patent,

this code having the code call 267 by which the office selector relay 267S is energized to release relay 4ST, and channel 5b is energized over contact *g* of relay 267S and the left-hand contact *a* of lever 4SG to effect the operation of relay 4LHS in Fig. 2D to its reverse position, thereby energizing relay over wire 22, and relay LAPS releases relay LACT to disconnect the track battery from the right-hand end of section AT.

Relay RATR therefore releases, energizing relay RATB, and then relay RATF releases, energizing relay RAFS, which initiates the operation of relay RACT. If relay 2LAHP is released, relay RACT is caused to supply 75 code to the rails of section AT at the left-hand end, and the operation of relay LATR in response to this code picks up relay LATF, which energizes the decoding transformer DT3, causing relay 4LAH to become energized. Relay LACT is operated by feed back impulses supplied by transformer DT3, so that relay RATF is energized to disconnect terminal B from channel 12a and to initiate the transmission of an indication code by which relay ATK is released and lamp AKE extinguished.

Relay 4LAH now energizes the route relay 4LBP by completing a circuit from terminal B over contacts *e* of relays 3TR and 3WLS, wire 23, contact *a* of relay 4LAH, wire 29, contacts *a* of relays 4RHS and 3NWP, contact *e* of relay 3WP, reverse contact *a* of relay 4LHS through relay 4LBP to terminal C. The opening of back contact *a* of relay 4LBP releases the approach locking relay 4LAS, and the closing of back contact *c* of relay 4LAS completes a circuit for mechanism 4LAG which may be traced from terminal B at front contact *a* of relay 4LBP over front contact *c* of relay 4RAS, back contact *b* of relay 3TER, back contact *c* of relay 4LAS, left-hand contact *d* of relay 3WP, wire 30, back contact *d* of relay 4LAD, wire 32, through the winding of mechanism 4LAG, wire 31, back contact *b* of relay 4LAD, wire 33, contact *b* of relay 4LBP, and contacts *c* of relays 4LHS and 4RHS to terminal C, causing signal 4LA to indicate caution and releasing relay 4LGP.

In the event signal 2LA indicates caution or proceed, relay 2LAHP is energized and 180 code is supplied to section AT by relay RACT. In that case, relay 2LAD is energized along with relay 2LAH and contacts *b* and *d* of relay 2LAD are picked up to reverse the polarity of the current supplied to mechanism 2LAG, causing signal 2LA to indicate proceed. When the train governed by signal 4LA enters section 3T, relay 3TR and its repeating relay 3TP release, releasing relay 3TKS to connect terminal B to channel 10b and to initiate the transmission of an indication code as described in the Jackel patent, by which relay 3TK is energized to light lamp 3TKE in the track diagram. The opening of contact *e* of relay 3TR releases relay 4LBP, which deenergizes mechanism 4LAG to restore signal 4LA to stop and causes relays 4LGP and 4LAS to be reenergized. Relay 4LHS is restored to normal by the energization of its lower winding over contact *a* of relay 3TKS, but relay LAPS which has been maintained energized over wire 22 independently of relay 4LHS by the closing of back contact *d* of relay 4LAS is now held energized over back contact *d* of relay 3TP. After section 3T is vacated, relay LAPS is held energized over its own front contact *a* and back contact *b* of relay 4LAH.

When the train enters section AT, the shunting of the track relay LATR stops its operation,

and relays LATF and 4LAH release. Transformer J3 ceases to supply feed back impulses to relay RATR, so that relay RATF releases and initiates the transmission of an indication code by which relay ATK is energized and lights lamp AKE to indicate the occupied condition of the block section AT.

After the train enters section 1T, relay RACT remains released due to the opening of contact e of relay 1TP, and when section 1T is vacated, the code operation of relay RACT is resumed and if section AT is vacant, relay LATR responds to pick up relay LATF, reenergizing transformers DT3 and J3 and relay 4LAH. The opening of back contact b of relay 4LAH releases relay LAPS, which causes relay LACT to assume its energized position to supply energy steadily to the rails of section AT. Relay RACT is now being operated at the .75 code rate, and relay RATR picks up as soon as relay RACT assumes its released position. The opening of back contact b of relay RATR holds relay RACT released, and relay RATR therefore remains picked up, releasing relays RAES and RATE, which completes the restoration of the apparatus to its normal inactive condition as shown.

To clear signal 2RA, the operator moves lever 2SG to the right with lever 1SW normal and presses the starting button 2STB to energize the starting relay 2ST, whereby a control code is initiated having the code call 234 by which the selector relay 234S is energized and relay 2RHS is operated to reverse over channel 1a.

The reversal of the traffic relay LAFS is required in this instance and this is accomplished automatically. When button 2STB is operated, relay 2STS is picked up along with relay 2ST over contacts a and b of button 2STB and contacts c of levers 2SG and 1SW. Relay 2STS is held picked up until relay 2ST releases over a stick circuit extending to terminal B over contact a of relay 2ST and contact i of relay 234S, and to terminal C over contact a of relay 2STS and contacts c of levers 2SG and 1SW. The closing of contact c of relay 2STS energizes relay 4ST, so that following the transmission of the code 234 by relay 2ST and the release of relays 2ST and 2STS, a second code is transmitted having the code call 267 in which channel 4b is energized over contacts b of relays ATK, 1TK, and 2STS, contacts b of levers 1SW and 2SG, contacts e of lever 4SG and relay 3TK or contact e of lever 3SW, and contact f of relay 267S. Relay LAFS is operated to reverse over channel 4b by this second code and initiates the code operation of relay LACT, and also energizes the slow release relay LAFSP to maintain the circuit for relay LAPS open. Relay RATR operates periodically, energizing relay RATE and maintaining relay RATF picked up. Transformer DT1 is energized over contact c of relay RATE, and relay 2RAH becomes energized to clear signal 2RA by a sequence of operations similar to those described for signal 4LA in the preceding example. More particularly, relay 2RBP is energized over the circuit extending from terminal B over contacts e of relays 1TR and 1WLS, wire 41, contact a of relay 2RAH, wire 48, contacts a of relays 2LHS and 1NWP, contact e of relay 1WP, and the reverse contact a of relay 2RHS. Relay 2RBP picks up and by opening its back contact a, releases relay 2RAS, which completes a circuit for mechanism 2RAG. Assuming that .75 code is being received, the decoding relay 2RAD is released and the circuit for mechanism

2RAG extends from terminal B over front contact a of relay 2RBP, contact e of relay 2LAS, contact b of relay 1TER, back contact c of relay 2RAS, normal contact d of relay 1WP, wire 49, back contact d of relay 2RAD, wire 50, the winding of mechanism 2RAG, wire 51, back contact b of relay 2RAD, wire 46, contact b of relay 2RBP, contacts c of relays 2RHS and 2LHS to terminal C. In this case, mechanism 2RAG is energized in a direction to cause signal 2RA to indicate caution, and when relay 2RAD is energized, the polarity of the current supplied to mechanism 2RAG is reversed to cause signal 2RA to indicate proceed. The opening of contact b of the approach locking relay 2RAS disconnects terminal B from wires 34 and 35 and thereby releases a section locking relay RAES, which opens its contacts b and c in the circuits for relays RACT and RAES. The feed back circuit for relay RACT including wire 27 is also open at contacts b of relays 2RHS and 1RWP so that feed back impulses are not transmitted at this time.

When the train governed by signal 2RA enters section 1T, relays 1TR, 1TP, and 1TKS release and relay 2RHS is restored to normal, and an indication code is transmitted by which relay 1TK is energized over channel 10a to light lamp 1TKE on the track diagram. Relay 2RBP releases to restore signal 2RA to stop and reenergizes relays 2RGP and 2RAS.

When the train enters section AT, relays RATR, RATF, RATE, and 2RAH release, and relay RATF initiates the transmission of an indication code by which relay ATK is energized over channel 12a to light lamp AKE.

When section 1T is vacated, relays 1TR and 1TP pick up, relay RAES is reenergized by the closing of contact b of relay 1TR, and the feed back circuit for relay RACT is prepared by the closing of contact e of relay 1TP and contact b of relay RAES.

The code operation of relay LACT ceases when the train enters section 3T, due to the opening of contact e of relay 3TP, and when section 3T is vacated, the code operation of relay LACT is resumed, and if relay RATR responds, relays RATF and RATE become energized and relay RACT is operated to generate feed back impulses which energize relay LATR. The closing of contact b of relay LATR restores relay LAFS to normal, causing relay LACT to become steadily energized, whereupon the system restores itself to the normal inactive condition as shown.

To clear signal 2RB, the operator moves levers 1SW and 2SG to the right and then presses the starting button 2STB. Relay 2STS is not operated because its circuit is open at contact c of lever 1SW, and only the code 234 is transmitted, this code operating relays 1WS and 2RHS to reverse. These relays may also be operated by successive codes so as to enable the operator to verify the position of the switch before clearing the signal, as will readily be understood. Relay 1WS operates switch 1W to reverse, releasing relays 1WP and 1NWP, and then energizing relay 1WP reverse when the switch assumes its reverse position, whereupon relay 1RWP becomes energized and by closing its contact d completes a circuit for energizing relay RBPS extending over wire 36 to terminal B at contact d of relay 2RHS. Relay RBCT is released by the opening of back contact c of relay RBPS, deenergizing section BT and releasing relay LBTR, whereupon relay LBTF picks up and relay LBTF releases to energize the traffic relay

75

LBFS. The closing of front contact *b* of relay LBFS completes a circuit for periodically energizing relay LBCT so that relay LBCT which may be traced from terminal B at contact *c* of relay 3WLS over wire 37, contacts *b* of relay LBTR and of the code transmitter 75CT, front contact *b* of relay LBFS, over wire 38 and contact *f* of relay 3NWP to wire 40, or from wire 38 over contact *c* of relay 3TR, wire 39, and contact *b* of the directional stick relay LBDS to wire 40, and thence over back contact *c* of relay LBDS through relay LBCT to terminal C, is caused to supply 75 code to the rails of section BT at the right-hand end. The operation of relay RBTR in response to this code picks up relay RBTF which energizes transformer DT2 causing the code detector relay 2RBD to become energized. Relay RBCT is operated by impulses supplied through transformer J2 by transformer DT2 to supply feed back impulses to section BT, so that relay LBTF is energized to disconnect terminal B from channel 12b and to transmit an indication code by which relay BTK is released and lamp BKE extinguished.

Relay 2RBD now energizes the route relay 2RBP by completing a circuit from terminal B over contacts *e* of relays 1TR and 1WLS, wire 41, contact *c* of relay 2RBD, wire 42, the normal contact *b* of relay 4LHS, contact *a* of relay 1RWP, contact *e* of relay 1WP, and the reverse contact *a* of relay 2RHS through relay 2RBP to terminal C. Relay 2RBP picks up and releases relay 2RAS to complete the circuit for mechanism 2RBG which may be traced from terminal B at front contact *a* of relay 2RBP, front contact *c* of relay 2LAS, contact *b* of relay 1TER, back contact *c* of relay 2RAS, reverse contact *d* of relay 1WP, wire 43, front contact *b* of relay 2RBD, wire 44, through the winding of mechanism 2RBG, wire 45, front contact *d* of relay 2RBD, wire 46, contact *b* of relay 2RBP and contacts *c* of relays 2LHS and 2RHS to terminal C. The relative polarity of the current in this circuit is such that signal 2RB is caused to indicate "proceed at slow speed."

When the train governed by signal 2RB enters section 1T, relay 1TR releases to initiate operations similar to those above described in connection with signal 2RA, whereby signal 2RB is restored to stop and relay 2RHS to normal.

The directional stick relay RBDS becomes energized upon the release of relay 1TP over contacts *f* of relays 1TP and 1RWP, wire 47, and front contact *a* of relay 2RBD, and when the train enters section BT, relays RBTR, RBTF, and 2RBD release, relay 2RBD completing a stick circuit to hold relay RBDS energized. The transmission of feed back impulses by transformer DT2 ceases and consequently relay LBTF releases, initiating the transmission of an indication code to energize relay BTK over channel 12b and light lamp BKE to indicate the occupancy of section BT.

By operating relay 2RHS again to reverse before section BT is vacated, a following train may be admitted to the route. In this case the route relay 2RBP is energized over contact *e* of relay RBDS, and mechanism 2RBG is supplied with current of the opposite polarity over contacts *b* and *d* of relay RBDS to cause signal 2RB to indicate "caution slow speed."

The operations involved in restoring the track circuit system for section BT to normal are similar to those already described for section

AT, and a description is therefore deemed unnecessary.

To clear signal 4LB, with the system in its normal inactive condition as shown, the operator reverses lever 3SW and moves lever 4SG to the left and then presses button 4STB. The resulting operations in this case with respect to the track circuit system are similar to those described above for the similar but oppositely directed track circuit system by which signal 2RA is controlled, and involve the transmission of two control codes, one for reversing the traffic relay at the exit end of the block, relay RBFS in this case, which is controlled over channel 4a, and the other for reversing the entering end signal control relay, which in this case is relay 4LHS, controlled over channel 5b, and for also energizing relay 3WS in the reverse direction over channel 3b, in order to reverse switch 3W in the event this switch is in its normal position as shown. The reversal of relay RBFS causes relay RBCT to supply 75 code to the rails of section BT, relay RBCT being energized over the circuit from terminal B over contact *f* of relay 2RAS and contact *c* of relay 1TP, or from terminal B over contact *b* of relay 1NWP, and thence over contact *c* of relay 1WLS, wire 59, contact *b* of the code transmitter 75CT, contact *a* of relay RBFS, contact *c* of relay RBDS, through relay RBCT to terminal C. In the preceding example, the two codes 234 and 267 were issued in their relative order of code superiority, code 267 following code 234 in accordance with the normal mode of operation of the remote control system, but if the two codes are issued in that order in the present case the track circuit system would be set into operation by the reversal of the traffic relay RBFS before the signal control relay 4LHS is reversed, and relay 4LHS being in its normal position would complete a circuit for relay LBCT from transformer J4 over wire 51 to terminal C at contact *b* of relay 3NWP or 4LHS, which would cause the transmission of feed back impulses to restore relay RBFS to normal and thereby restore the track circuit system to its inactive condition before relay 4LHS is reversed by code 267. It is therefore necessary to reverse the normal order of code transmission in this instance, and this is accomplished as shown in Fig. 1 by including a back contact *e* of relay 4STS in the initiating circuit for code 234.

It will be seen that if button 4STB is pressed when contacts *c* of levers 4SG and 3SW are closed, relay 4STS is picked up along with relay 4ST, and then relay 2ST is picked up over front contact *c* of relay 4STS but is rendered incapable of initiating code 234 by the opening of back contact *e* of relay 4STS. The closing of contact *b* of relay 4ST initiates code 267 for reversing relay 4LHS, whereupon relays 4ST and 4STS release, the release of relay 4STS allowing the transmission of the code 234 by relay 2ST, in which channel 4a is energized over contacts *b* of levers 4SG and 3SW to effect the reversal of relay RBFS.

The circuits by which signal 4LB is controlled by the track circuit system are generally similar to those for the similar signal 2RB already described. In the present case, relay 3WP is reversed, relay 3NWP is released and relays 3RWP and 4LBD are energized. Relay 4LBP picks up over a circuit which differs from that traced above in that it extends from wire 28 over contact *c* of relay 4LBD, wire 53, contact *b* of

relay 4LHS and contact *a* of relay 3RWP. Contact *c* of relay 3NWP in the pick-up circuit for relay LWBS including wire 54 is now open, and relay LBWS is released by the opening of its stick circuit including wire 55, when relay 4LAS is released by the operation of relay 4LBP. Mechanism 4LBC is energized over a branch of the circuit traced above for mechanism 4LAG which includes the reverse contact *d* of relay 3WP, wire 56, contact *b* of relay 4LBD, wire 57, the winding of mechanism 4RBG, wire 58, contact *d* of relay 4LBD to wire 33 and thence as already traced, to terminal C. The directional stick relay LBDS is picked up over the circuit including wire 60 when the train governed by signal 4LB enters section 3T, and functions like the corresponding relay RBDS already described.

It may be that to effect a "meet," the operator will clear two signals such as 2RB and 4LA or signals 2RA and 4LB at the same time. The simultaneous clearing of signals 2RB and 4LA may be accomplished in an obvious manner since they are governed independently by different codes but the simultaneous clearing of signals 2RA and 4LB requires consideration because the clearing of these signals involves the transmission of codes to the same two stations, but in different orders as already explained.

Assuming that lever 1SW is normal and lever 2SG in its right-hand position, and that lever 3SW is reversed and lever 4SG is in its left-hand position, the operation of button 2STB will pick up relays 2ST, 2STS, and 4ST, and the subsequent operation of button 4STB will pick up relay 4STS, while if button 4STB is operated first, relays 4ST, 4STS, and 2ST will be picked up by the operation of button 4STB and relay 2STS by the operation of button 2STB. In either case, code 267 is the first to issue, the initiating circuit for code 234 being open at back contact *e* of relay 4STS. Code 267 reverses the signal control relay 4LHS by the energization of channel 5b over contact *a* of lever 4SG, and also reverses relay 3WS by the energization of channel 3b, but the traffic relay LAFS is not operated at this time because channel 4b controlled by relay 267S is now open at back contact *b* of relay 2STS.

Relay 4ST and 4STS are released by relay 267S in the usual manner in response to the transmission of code 267 to allow code 234 to follow, as above described in connection with signal 4LB, but as soon as relay 4STS releases, relay 4ST is reenergized over back contact *d* of relay 4STS and front contact *c* of relay 2STS to store a second code 267 for transmission following the delivery of code 234. Code 234 reverses relay RBFS and also relay 2RHS, and also energizes relay 1WS in the normal direction, the lever positions now being such that channels 1a, 4a and 7a controlled by relay 234S are energized, and relay RBFS energizes the track circuit system for section BT to effect the clearing of signal 4LB, relay 4LHS having been reversed by the preceding code 267 as already described. Relays 2ST and 2STS are released by relay 234S in response to the transmission of code 234 but since relay 4ST is still energized, code 267 is again transmitted. Channel 4b controlled by relay 267S is now energized over back contact *b* of relay 2STS, since this relay was released by the preceding code 234, by which relay 2RHS was energized. Relay LAFS is reversed by the second code 267 to energize the track circuit system for section AT as required

for the clearing of signal 2RA, and channels 3b and 5b are also energized to maintain relays 3WS and 4LHS reversed.

It is to be noted that if channel 4b is energized when the first code 267 is transmitted, as would be the case if contact *b* of relay 2STS were not included in its circuit, relay LAFS would be reversed by this code and would set the track circuit system for section AT into operation but since relay 2RHS at that time would be in its normal position, relay RATC would be operated by a feed back impulse supplied by transformer DT1 to pick up relay LATR, which relay would restore relay LAFS to its normal position. Relay LAFS would be reversed again by the second code 267 as above described, with the same end result. The purpose of contact *b* of relay 2STS is therefore merely to eliminate an idle operation of the wayside apparatus.

Although I have herein shown and described only one form of centralized traffic control apparatus embodying my invention, it is understood that various changes and modifications may be made therein within the scope of the appended claims without departing from the spirit and scope of my invention.

Having thus described my invention, what I claim is:

1. In a centralized traffic control system having signals at each end of a stretch of railway for governing traffic movements into the stretch, a code type communication system having stations at said signal locations for governing said signals from a central office, a traffic relay and a signal control relay at each station, a circuit for clearing each signal arranged to be energized in accordance with traffic conditions in said stretch when the traffic relay at the other station is reversed provided the signal control relay for such signal is also reversed, means at each station governed by the signal control relay at the other station in its normal position for restoring the adjacent traffic relay to its normal position, a signal lever for each signal, a starting button, a starting relay and a storing relay for each station, all located at a control office, means controlled by each starting relay when energized for initiating the transmission of a code for operating the signal control relay at the corresponding station to a position reflecting that of its lever or if such lever is in its normal position for operating the traffic lever at such station to reverse, provided the lever for the signal at the other station is reversed, means responsive to the momentary operation of each starting button for energizing the associated starting relay, and for also energizing the associated storing relay provided the signal lever associated therewith is reversed, means for releasing each energized starting relay and storing relay upon the delivery of a code to the corresponding station, means controlled by the storing relay for either station when energized for energizing the starting relay for the other station to thereby initiate the transmission of a second code, and means effective when both starting relays are energized for causing the code initiated by the one having the associated storing relay energized to precede the code initiated by the other starting relay irrespective of the normal order of transmission of said codes.
2. In a centralized traffic control system, a code type communication system having a first and a second station located at the opposite ends of a stretch of railway track, a signal at each

station for governing traffic movements into said stretch, a first and a second panel at a control office for the control of said stations each including a signal lever, a starting button and a starting relay, a circuit controlled by each starting relay when operated for initiating the transmission of a code to the corresponding station by said code system, a circuit for operating each starting relay closed in response to the operation of the associated starting button, a circuit controlled by the starting button of each panel for operating the starting relay for the other panel if such button is operated when the signal lever associated therewith is in its signal clearing position, means dependent upon the relative order of transmission of the codes transmitted when both starting relays are operated for controlling one signal or the other in accordance with the position of its signal lever, means normally effective to cause the code for the first station to precede the code for the second station when said two codes are initiated by the operation of the starting button of the first panel, and means for reversing the normal order of transmission of said codes when they are initiated by the operation of the starting button of the second panel.

3. In a centralized traffic control system, a code type communication system having a first and a second station located at the opposite ends of a stretch of railway track, a signal at each station for governing traffic movements into said stretch, a first and a second panel at a central office for the control of said stations, each including a signal lever, a starting button, a starting relay and a storing relay, a circuit controlled by each starting relay when operated for initiating the transmission of a code to the corresponding station by said code system, a circuit for operating each starting relay closed upon the operation of the associated starting button, a circuit for operating each storing relay when the associated starting button is operated provided the signal lever of the same panel is in its signal clearing position, a circuit closed by each storing relay when operated for operating the starting relay of the other panel provided the storing relay of such other panel is in its normal position, whereby codes may be initiated for transmission to both stations by the operation of either starting button, means dependent upon the relative order of transmission of said codes for controlling one signal or the other in accordance with the position of its signal lever, means normally effective when both starting relays are operated for causing the code for the first station to precede the code for the second station, and means controlled by the storing relay of the second panel when operated for reversing the relative order of transmission of said two codes.

4. In a centralized traffic control system, a code type communication system having a first and a second station located at the opposite ends of a stretch of railway track, a signal at each station for governing traffic movements into said stretch, a first and a second panel at a central office for the control of said stations, each including a signal lever, a starting button, a starting relay and a storing relay, a circuit controlled by each starting relay when operated for initiating the transmission of a code to the corresponding station by said code system, a circuit for operating each starting relay closed upon the operation of the associated starting button, a circuit for operating each storing relay when the

associated starting button is operated provided the signal lever of the same panel is in its signal clearing position, a circuit closed by each storing relay when operated for operating the starting relay of the other panel provided the storing relay of such other panel is in its normal position, whereby codes may be initiated for transmission to both stations by the operation of either starting button, means dependent upon the relative order of transmission of said codes for controlling one signal or the other in accordance with the position of its signal lever, means normally effective when both starting relays are operated for causing the code initiated by the starting relay of the first panel to precede that initiated by the starting relay of the second panel, means controlled by the storing relay of the second panel when operated for causing the code initiated by the associated starting relay to precede said code initiated by the starting relay of the first panel, and means controlled by the storing relay of the first panel when both storing relays are operated for causing the reoperation of the starting relay for the second panel to effect the transmission of a second code to said second station.

5. In a centralized traffic control system, a code type communication system having a first and a second station located at the opposite ends of a stretch of railway track, a signal at each station for governing traffic movements in accordance with traffic conditions in said stretch, a signal control relay at each station for manually governing the adjacent signal, a traffic relay at each station, one of which when reversed establishes one direction and the other the opposite direction for traffic movements into said stretch, a control panel at a central office for each station each including a signal lever, a starting button, a starting relay and a storing relay, means for operating each starting relay when the starting button of the same panel is operated, and also when the storing relay of the other panel is operated, means controlled by each starting relay when operated for initiating the transmission of a code by said code system, by which the signal control relay at the corresponding station is operated when its signal lever is in its signal clearing position or by which the traffic relay at such station is operable to reverse provided the signal lever for the signal at the other station is in its signal clearing position, means governed by each signal control relay in its normal position for restoring the traffic relay at the other station to normal, means for operating each storing relay in response to the operation of the associated starting button provided the signal lever for the same panel is in its signal clearing position, and means governed by at least one of said storing relays for governing the relative order of transmission of said two codes initiated by said starting relays when either signal lever is in its signal clearing position so that for either direction of traffic movement that one of the codes by which the signal control relay is operated precedes the one by which the traffic relay at the other station is reversed.

6. In a centralized traffic control system, a code type communication system having a first and a second station located at the opposite ends of a stretch of railway comprising two parallel tracks, signals at said stations for governing traffic movements into said stretch, a signal control relay and a traffic relay at each station, circuits for the signal at the first station controllable in

accordance with traffic conditions in one of said tracks by the traffic relay at the second station and by the signal control relay at the first station, circuits for the signal at the second station controllable in accordance with traffic conditions in the other track by the traffic relay at the first station and by the signal control relay at the second station, a control panel at a central office for each station each including a signal lever and a starting button, a starting relay in each panel operable by the associated button, means controlled by each starting relay when operated for initiating the transmission of a code by said code system by which the signal control relay at such station is operable in accordance with the position of its signal lever or by which the traffic relay at such station is operable to reverse provided the signal lever for the signal at the other station is in its signal clearing position, a circuit controlled by each signal control relay in its normal position effective when the corresponding track in said stretch is unoccupied for restoring the traffic relay at the other station to its normal position, a storing relay in each panel, a circuit for operating each storing relay when the associated starting button is operated provided the signal lever for the same panel is in its signal clearing position, a circuit controlled by each storing relay when operated for operating the starting relay for the other panel, means effective when the storing relay of the panel for the second station is operated to delay the transmission of a code to the first station until such storing relay is released, means for restoring each operated storing relay to its normal position along with the associated starting relay upon the transmission of the corresponding code, and means effective if the storing relay of the first panel is in its operated position when the starting relay for the second panel is restored to normal for reoperating said starting relay.

7. In a centralized traffic control system, a code type communication system having a first and a second station located at the opposite ends of a stretch of railway track, a reversible coded track circuit system having a track relay at each end adapted to reflect traffic conditions in said stretch and having a transmitter relay at each end which in one position connects a source of current to the rails of the stretch and in another position conditions the adjacent track relay to respond to current received over the rails of the stretch, a traffic relay and a signal control relay at each station, a signal at each station for governing traffic movements into said stretch, a circuit for clearing each signal controlled by the adjacent signal control relay in accordance with the periodic operation of the adjacent track relay, circuits rendered effective when either traffic relay is in its operated position for causing the code transmitter adjacent thereto to supply period-

ically interrupted current to the track rails of the stretch, means effective when the traffic relay and signal control relay at the second station are both in their normal positions for maintaining the code transmitter at that end of the stretch in said one position to supply steady current to the track rails, a first repeating relay controlled over a front contact of the track relay at the first station, a second repeating relay controlled over a back contact of said track relay and a front contact of said first repeating relay, a circuit for operating the traffic relay at the first station controlled over back contacts of the adjacent track relay and of said first repeating relay, said circuit also including a front contact of said second repeating relay, a restoring circuit for each traffic relay effective to restore such relay to its normal position when the adjacent track relay becomes energized, a signal lever for each signal located at a control office, and means including said communication system for operating each signal control relay to a position which reflects that of the corresponding signal lever and for also operating the traffic relay at the second station to its reverse position when the signal lever for the signal at the first station is in its signal clearing position.

8. In a centralized traffic control system, a code type communication system having a first and a second station located at the opposite ends of a stretch of railway track, a signal at each station for governing traffic movements into said stretch, a first and a second panel at a central office for the control of said stations each including a signal lever, a starting button, a starting relay and a storing relay, indication means at said office controlled by said communication system reflecting traffic conditions in said stretch, means for operating each starting relay when the associated starting button is operated and also when the storing relay for the other panel is operated but only if said indication means indicates that the stretch is unoccupied, means for operating each storing relay when the associated starting button is operated provided the signal lever of the same panel is in its signal clearing position, a circuit controlled by each starting relay when operated for initiating the transmission of a code to the corresponding station by said communication system, means controlled jointly by the codes transmitted to said stations when the signal lever of either panel is in its signal clearing position for clearing the signal at the corresponding station, and means for restoring each operated storing relay to its normal position along with the associated starting relay upon the transmission of a code to the corresponding station.
